WITNESS:

Patented June 2, 1925.

UNITED STATES PATENT OFFICE.

FRANK D'ONOFRIO, OF WILMINGTON, DELAWARE.

SHOOTING GALLERY.

Application filed August 27, 1923. Serial No. 659,586.

To all whom it may concern:

Be it known that I, FRANK D'ONOFRIO, a citizen of the United States, residing at Wilmington, in the county of New Castle and State of Delaware, have invented new and useful Improvements in Shooting Galleries, of which the following is a specification.

This invention relates to a toy made in the form of a shooting gallery, the general object of the invention being to provide manually operated means for operating a series of targets and at the same time operating a gun, the bullets from which will strike the targets as they reach a certain point.

Another object of the invention is to provide means for resetting the targets and for catching the bullets from the gun.

20 This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote 30 like or corresponding parts throughout the several views, and in which:—

Figure 1 is a side view of the invention.

Figure 2 is a section on line 2—2 of

Figure 1.

35 Figure 3 is a partial plan view.

Figure 4 is a sectional detail view through part of the gun.

40 In these views, 1 indicates a base which is of hollow construction and in which is journaled a shaft 2, the front end of which is provided with a crank handle 3 by which the shaft may be turned. A figure 4, made to represent a man holding a gun 5, is mounted on the base and this gun is formed 45 with a magazine 6 to hold bullets and it is provided with a spring actuated projector 7 for ejecting the bullets from the gun. This projector is actuated by the pivoted lever 8 which has its lower end passing into the 50 base where it is engaged by the cams 9 on the disc 10 which is fastened to the shaft 2. The lever is pivoted at 11 to a part of the figure and the parts are so arranged that as the shaft is turned the cams will rock 55 the lever so as to retract the projector and then when the lever is released by the cam

the spring will cause the projector to spring forwardly and eject a bullet from the gun. A pulley or sprocket 12 is fastened to the shaft and a second pulley 13 is fastened to a stub shaft 14 which is carried by the hollow upright 15 which is fastened to the base. An endless chain or belt 16 passes over the members 12 and 13 and this belt or chain carries the ears 17 to which the stems 18 are pivoted, each stem carrying a target 19 which is preferably made in the form of a bird. These parts are so arranged that as a target reaches the upper part of the member 13 it will be in the path of a bullet 60 ejected from the gun so that it will be struck by said bullet and the force of the blow will cause the bird and stem to drop rearwardly, due to the pivoted connection 65 of the stem with the belt or chain. As the parts move downwardly the stem will come in contact with the cam 20 which will return the stem and bird to the normal position so that the bird will be in position to 70 be again shot at when it reaches the top 75 part of its path. A net 21 is carried by the uprights 22 at the rear of the device for catching the bullets and a drawer 23 is arranged at the bottom of the net for receiving the bullets caught by the same so that 80 the bullets can be returned to the gun. 85

From the foregoing it will be seen that by rotating the handle 3 the shaft 2 will be turned so as to actuate the target carrying member and the ejector of the gun. The 90 parts are so timed that a target will reach the top part of its path just after the gun has been actuated so that the bullet will strike the target. The target will then be raised by the cam 20 and then the bullet 95 will be caught by the net and will drop into the drawer.

It is thought from the foregoing description that the advantages and novel features of my invention will be readily apparent.

I desire it to be understood that I may make changes in the construction and in the combination and arrangement of the several parts, provided that such changes fall 100 within the scope of the appended claims.

105 What I claim is:—

1. A device of the class described comprising a hollow base, a figure representing a man with a gun, supported on the base adjacent one end thereof, a projector in the gun, a vertically arranged lever pivoted to 110 a part on the figure with its upper end en-

gaging the projector, a shaft passing through the hollow base and having a crank on its outer end, a cam on the shaft for rocking the lever, a movable target, means for supporting the same adjacent the other end of the base and means for moving said target from the shaft.

2. A device of the class described comprising a hollow base, a shaft passing through the same and having its outer end provided with a crank, a cam disc on the shaft, a pulley on the shaft, a figure, representing a man with a gun, supported on the base, a spring actuated projector on the gun for projecting bullets therefrom, a vertically arranged lever pivoted to a part of the

figure and having its upper end engaging the projector and its lower end engaging the cam disc so that the bullets will be thrown from the gun when the shaft is rotated, an upright on the base, a shaft at the upper end thereof, a pulley on said shaft, an endless belt passing over said pulley and the first mentioned pulley, targets pivoted to the plate, the target which is uppermost being in line with the gun so that it will be struck by a bullet projected from the gun and knocked down and means for returning the target to normal position as the belt is rotated.

In testimony whereof I affix my signature.
FRANK D'ONOFRIO.
